UNITED STATES PATENT OFFICE.

T. CLARENCE HEISEY, OF NEWARK, OHIO, ASSIGNOR TO A. H. HEISEY & COMPANY, OF NEWARK, OHIO.

DESIGN FOR A FLORAL COMPORTIER.

Application filed March 15, 1923. Serial No. 5,483. Term of patent 3½ years.

To all whom it may concern:

Be it known that I, T. CLARENCE HEISEY, a citizen of the United States of America, residing at Newark, in the county of Licking and State of Ohio, have invented a new, original, and ornamental Design for a Floral Compotier, of which the following is a specification, reference being had to the accompanying drawing, forming a part thereof.

I claim—

The ornamental design for a floral compotier or similar article, as shown.

T. CLARENCE HEISEY.
